WEB WINDING MACHINE

Edwin M. Kwitek and Ernst Daniel Nystrand, Green Bay, Wis., assignors to Paper Converting Machine Co., Inc., Green Bay, Wis., a corporation of Wisconsin

Application July 16, 1952, Serial No. 299,198

10 Claims. (Cl. 242—56)

This invention relates to a web rewinding machine, and more particularly to a multiple stage core cutting and web rewinding machine wherein core lengths are fed into the machine, cut into individual cores or segments, wound with a web such as paper, and then removed from the machine.

An object of the invention is to provide a multiple stage core cutting and web rewinding machine wherein core lengths are received upon core shafts fixed in the machine, cut into individual cores or segments of desired lengths, and subsequently wound with a slit web, the wound cores being then stripped from the machine automatically. Another object of the invention is to provide a multiple stage machine of the class described in which a core is being cut into segments of desired length at one station while simultaneously a web is being wound upon another core at a second station, and at the same time a core having a web wound thereon is being stripped automatically from the machine at still another station. Still another object is to provide a web winding machine in which a plurality of core shafts are carried by a member intermittently driven whereby the core shafts are transferred from one station to another and are held at each station for a predetermined time while the various operations are being performed.

A further object of the invention is to provide a machine in which the driving mechanism is quickly and easily re-timed so that upon breakage of the web during the winding operation, the machine need not continue to operate through its preset cycle before another core shaft may be moved to web winding position and there have a complete length of web wound thereon. A still further object of the invention is to provide in a web rewinding machine a stripping means that is automatically actuated when a wound core is moved to core stripping position to strip the wound core from the core shaft, and which is automatically deactuated after each wound core is stripped from the machine. Yet another object is to provide retractile shaft supporting arms which engage the core shafts during certain of the operations while retracting from engagement with the shafts during the core stripping and core insertion operations. It is a still further object of the invention to provide a means for placing a static charge upon the severed tail of the rewound webbing whereby the tail clings firmly to the wound core and the use of adhesives, etc., for this purpose is eliminated. Still another object is to provide core cutting knives or disks that are pivotally mounted to permit movement of the cores into and out of the core cutting station. A further object of the invention is to provide a core cutting and web rewinding machine having rapid movement while performing accurate operations, whereby a very large number of wound cores are delivered by the machine in a very short period of time and in an accurately wound condition to provide a neat appearing article. Further objects and advantages of the invention will appear as the specification proceeds.

Our invention may best be understood by referring to the drawings, which illustrate a preferred embodiment of our invention, and in which—

2

Figure 1 is a perspective view of the web rewinding machine embodying our invention; Fig. 2, a similar perspective view taken from the opposite end of the machine; Fig. 3, a side view taken from a point inwardly of the right end frame or wall of the machine looking toward the left, and in which parts of the apparatus are shown in section; Fig. 4, a side view taken from a point inwardly of the left end frame or wall, as indicated by the line 4—4 of Fig. 7; Fig. 5, an enlarged, detailed side view of the turret and mandrels and core cutting knives taken from a point inwardly of the right end frame or wall of the machine looking toward the left, and in which parts of the apparatus are shown in section; Fig. 6, a diagrammatic view of the shafts and driving mechanism shown stripped from the machine; Fig. 7, a cross-sectional view taken on the line 7—7 of Fig. 5; Fig. 8, an enlarged cross-sectional view of the retractile mandrel support arms; Fig. 9, an enlarged cross-sectional view of the timing gear assembly looking toward the rear of the machine and taken on the line 9—9 of Fig. 4; Fig. 10, a fragmentary perspective view of the web severing knife and actuating mechanism; Fig. 11, a fragmentary view showing a detailed cross section of the web severing knife; Fig. 12, a side elevational view of the switch arrangement and actuating arm for triggering the web severing knife and the core stripping mechanism; Fig. 13, a front end view of the structure shown in Fig. 12 and in which the turret driving member is included; Fig. 14, a broken perspective view of the core cutting knives; Fig. 15, an exploded perspective view showing an individual core cutting knife assembly in spaced-apart relationship; Fig. 16, a detailed cross-sectional view of a web slitting knife or disk received within a mating groove provided in the secondary bed roll; and Fig. 17, a perspective view of the mechanism for withdrawing the web slitting knives from engagement with the bed roll and in which the parts are shown in spaced-apart relationship.

The perspective views shown in Figs. 1 and 2 indicate the general structure of our multiple stage core cutting and web rewinding machine and locate the relative positions of the individual parts, etc., comprising the machine. Referring to these figures, the various parts are shown mounted upon a frame A having a left end wall B and a right end wall C. The end walls or frames B and C are connected rigidly at the bottom by cross spacers D and at the top by two additional spacers. Suspended from the upper tubing E are the mandrel assembly F, the mandrel driving assembly G, and the core cutters H. Mounted adjacent the lowermost mandrel is a core stripping mechanism J. A clutch and driving assembly is indicated by the letter K and the gear train and shaft driving mechanism is indicated generally by the letter L. The roller assembly over which the web passes is indicated by the letter M.

Referring to Figs. 3 and 4, a parent or mill roll 10 having a shaft 11 extending therethrough is supported by a pair of spaced brackets 12 each having an elongated slot 13 therein. The brackets in turn are supported upon a base or floor by a suitable supporting structure 14 which may be removably secured to the end frames by bolts, etc. The ends of the shaft 11 are received within the slots 13 which permit movement of the shaft within the slots as the web is removed from the parent roll and the size of the roll is thereby decreased. The slots 13 extend downwardly as well as outwardly and the forces of gravity acting upon the parent or mill roll 10 cause it to move downwardly in the slots 13 until movement is arrested by some intercepting member. A web 15 is shown as it is being delivered from the parent roll 10, and the web, which is wound upon the periphery of the parent roll 10, frictionally engages a delivery roller 16 that is journaled upon suitable bearings in the

supporting brackets 14. The delivery roller 16 is driven through a suitable belting arrangement which will be later described. The parent roll 10 may also be equipped with a gearing mechanism permitting lateral adjustment of the roll for purposes of aligning the web, etc.

The web 15 is drawn upwardly over an idler roller 17 which is freely rotatable upon a bracket 18 secured to the end frames or walls B and C of the machine. The web 15 is then drawn upwardly and passes over another idler roller 19 which is journaled upon suitable bearings within the end frames or walls of the apparatus. The idler roller 17 takes up any slack in the web 15 while the idler roller 19 is used to change the direction of the web. The web 15 then passes under a felt-covered feed or pull roller 20 which is driven through a gear train that will be later described. The web passes between the feed roller 20 and a secondary perforator roll 21, which is also driven, and then between the secondary perforator roll 21 and a perforator roll 22. The perforator roll 22 is equipped with a plurality of spaced perforating knives 23 that coact with recesses 24 in the secondary perforator roll to perforate or otherwise mark or segment the web 15 transversely. This arrangement is used when winding toilet paper, etc., and may be eliminated when winding other materials such as waxed paper, etc. The web then passes between the secondary perforator roll 21 and a secondary bed roll or web slitting roll 25 and thence around the roll 25 where the web is slit longitudinally into predetermined widths by the coaction of the slitting roll 25 with slitting knives 26 carried by a shaft 27. The web then passes between the secondary bed roll 25 and a bed roll 28. A guide roll 29 provided with a gear 30 which mates with a gear 31 of the bed roll (seen in Fig. 4) guides the web 15 about the periphery of the bed roll 28. The knife-equipped shaft 27 is pivotally mounted upon the end frames by means later described, while the rollers 20, 22, 21, 25 and 28 are all journaled in the end frames or walls B and C of the machine upon suitable bearings and are all driven rollers. The guide roll 29 is rotatably mounted in arms 32 which are secured to a shaft 33 by any suitable means. In the illustration, the arms 32 are split adjacent the shaft 33 and the split segments are drawn tightly about the shaft by bolts 34. A second arm 35 is keyed to the shaft 33 by pins 36 so that movement of the arm 35 pivots the shaft 33 and the arm 32. The shaft 33 is pivotally mounted within the end frames or walls B and C. A helical spring 37 is secured to the opposite end of the arm 35 and carries a rod 38 secured to a bracket 39. The bracket 39 is releasably locked to a shaft 40 by bolts 41. By this structure, the degree of engagement of the guide roll 29 and the gear 30 with the bed roll 28 may be adjusted by positioning the bracket 39 as desired upon the shaft 40 and locking the bracket in the selected position by means of the bolts 41. At the same time, the guide roll 29 and the gear 30 are yieldably held in engagement with the bed roll 28 by the spring 37, and the guide roll may be moved from engagement with the bed roll if it is subjected to an unusual lateral force. The gear 30 is locked to the guide roll 29 by means of a key 42.

The web 15 passes over the bed roll 28 and is wound upon cores mounted upon mandrels or core shafts 43 which are fixedly carried by a turret or spiders 44.

The mandrel assembly F is rotatably mounted upon depending brackets 45 which in turn are freely rockable about and carried by the upper cross tubing E. The turret 44 is a multiple stage turret and in the embodiment illustrated has six separate stations. A core receiving station is indicated by the letter a and at this station core lengths are inserted onto the core shaft or mandrel. This operation may be manual or a suitable mechanism (not shown) may be used to accomplish this result. In the sequence of operations, the turret 44 is rotated to the core cutting station b where a plurality

of axially-spaced cutting knives or disks 46 engage the core and cut it into predetermined lengths. For example, at this station a core length may be cut into individual cores or core segments upon which rolls of toilet paper are wound. The turret again rotates through an arcuate distance to the station c. No operation is performed upon the core at this station. The turret again rotates and in passing to the station d the cores are swept over a plurality of spaced glue applicator rollers or wheels 47 which apply a narrow band or ring of glue or adhesive to the individual core segments. From station d the rotation of the turret 44 moves the core, to which glue has now been applied, into the web winding station e. In moving from station d to the web winding station e, the core shaft engages the driving belt 48 while intermediate the two stations and is caused to rotate. Before reaching station e the core and core shaft approach closely the bed roll 28 and are, at this time, rotating at full speed and the proper speed for picking up the loose or leading ends of the web which have been severed and are pushed against the previously glued cores by means of springs later described. The glue that has previously been applied to the surface of the core causes the end of the web to adhere to the core, and the winding of a predetermined length of web onto the core is started.

While this takes place, the core shaft continues moving down, around and increasingly farther away from bed roll 28, until it reaches station e, where it continues to wind. After a substantial portion of the rolls have been wound at this station, the core shaft continues on towards the core stripping station f. The rolls are finished wound when the core shaft following is approaching bed roll 28 and the webs are severed.

In moving the core, which now has a web wound thereon, from station e to station f, the core shaft frictionally engages the lower edge 49 of an arm or bracket 50. The lower edge 49 of the bracket 50 is arcuate and corresponds with the arc through which the core is moved. The engagement of the bracket 50 with the periphery of the core shaft brakes the core shaft and a slow rotational motion is thereby imparted to the core shaft. It will be noted that in moving from the finished wound position between e and f, to station f, the core shaft moves out of engagement with the belt 48, and the continued rotational movement of the core and shaft is obtained solely by engagement with the lower surface or edge 49 of the bracket 50. The purpose of having the wound core rotate while moving between the finished wound position between e and f and the stripping station f is to insure engagement of the tail of the web, which has not been as yet secured to the filled core or roll and is flying free thereof, with a brush 51, mounted upon a supporting arm 52. A felt wiper 53 secured to the arm 52 contacts the periphery of the bed roll 28. The brush 51 extends longitudinally of the wound core and as the loose tail of the wound web wipes over the bristles of the brush, the tail is charged electrostatically with a polarity such that the tail is attracted to the wound roll by the electrostatic attraction between the two and lies securely thereagainst. The electrostatic applicator member or brush 51 may be made of many materials; however, we have found that nylon gives particularly desirable results and does not damage the tail of the web. At station f the wound cores are stripped from the core shaft and the turret again rotates to bring the empty core shaft into the core receiving station a, and the cycle of operation is completed.

Referring particularly to Figs. 2, 5, 14 and 15, the core cutting assembly H comprises a plurality of axially-spaced cutter assemblies 46 which are mounted upon a shaft 54. The shaft 54 is pivotally mounted in brackets 55 secured to a supporting shaft 56 by bolts 57 (seen in Fig. 2). The brackets 55 permit the shaft 54 to pivot 75 freely therein while the ends of the shaft are pivotally

carried in the hangers 45 which restrain the shaft from axial movement. The cutting assemblies 46 may be positioned axially along the shaft 54 at any desired points so as to cut the core length into individual cores or segments of the required length. It is to be noted that the first and thereafter alternate cutter assemblies 46 are mounted to engage the upper surface of the core, while the second and thereafter alternate cutter assemblies are mounted to engage the lower surface of the core.

The core cutter assemblies 46 each include a cutting knife or disk 58 rotatably mounted within a recess provided in a supporting block or freely rockable arm 59. The disks 58 are supported upon axles 60 mounted within the blocks 59 that are threaded to receive nuts 60a. The blocks 59 are equipped with collars 61 having a bore 62 therein adapted to rotatably receive the shaft 54. The blocks 59 are also equipped with annular recesses 63 which receive one end of the springs 64. Collars or cranks 65 having integrally-formed extensions 66 adapted to align with the blocks 59 when assembled are equipped with a bore 67 that lockably receives the shaft 54. The extensions 66 have a shoulder 68 that abut to provide a recess enclosing the disk 58 when the collars 65 are assembled with the block 59. The extensions 66 may also be equipped with annular recesses that are aligned with the recesses 63 in the block 59 when the collars 65 and block 59 are assembled. The recesses in the extensions 66 receive an end of the springs 64. Adjustable stop screws 69 equipped with lock nuts 70 extend through threaded bores in the extensions 66 positioned forwardly of the recesses.

In assembled condition as shown in Fig. 14, the collars 65 are locked to the shaft 54 by any suitable means such as a key, etc., while the block 59 and collar 61 are free to pivot upon the shaft 54 and the action of the springs 64 urges the block 59 away from the extensions 66. To prevent the block 59 from moving away from the extension 66 to a position releasing the spring 64, brackets 71 which are equipped with an aperture 72 are secured to the block 59 by means of a bearing bolt 73 extending through the apertures 72 and received within a threaded bore 74 in the side of the block 59. The brackets 71 are also equipped with elongated slots 75 receiving the bearing portion of a bearing bolt 76 extending therethrough and received within the threaded bore 77 provided in the side of one of the extensions 66. The block 59 and the extension 66 of the collars 65 may move apart under the urging of the spring 64 to the extent permitted by the elongated slot 75 in the bracket 71. However, the extent of movement within the slot 75 is determined by the position of an adjusting screw 78 equipped with a lock nut 79 which is received within a bore provided in the bracket 71 communicating with the upper portion of the slot 75. It is seen, then, that by appropriate axial positioning of the adjustable stop screws 69, the extent of movement of the block 59 toward the extension 66 may be limited while the spacing between the block 59, which carries the cutting knife, and the extensions 66, is determined by the adjustment of the screw 78. These adjustments accommodate accurate adjustment of the cutting knives.

The shaft 54 has secured thereto supports 80 and 81. The support 80 has a U-shaped end 82 upon which are mounted rotatable wheels 83. The wheels 83 engage the mandrel or core shaft 43 adjacent its free end to provide support for the core shaft during the cutting of the core. The support 81 has an extension 84 to which is rotatably secured a support wheel 85. The wheel 85 supports the core length while it is being cut. A driven roller 86 equipped with spaced-apart knurled portions 86a (Fig. 8) frictionally engages the cores 87 mounted upon the core shafts 43 when the cores and shafts are in core cutting station b. The roller 86 rotates the cores, which are at this point loose upon the core shafts 43, 75

and a complete and clean cutting of the core about the periphery is accomplished. The mountings for the core shafts 43 (to be described later) provide a clamp collar that also serves as a stop for limiting the extent of insertion of the cores 87 onto the shafts and each core is thereby properly positioned for cutting, etc., when it abuts the collar.

It can be seen in Figs. 3 and 5 that when the cores and shafts are in core cutting position at station b, the cutting disks or knives 58 extend into the line of movement of the cores and core shafts, and provision must be made to permit movement into and from the core cutting station b. To this end, the shaft 54 upon which the cutting knives are supported is pivotally mounted within the brackets 55 which secure it to the support shaft 56. During movement of the turret 44, and when the core cutting station b does not have a core and shaft therein, the weight of the core cutting assemblies 46 causes the shaft 54 to turn within the supports or brackets 55 and the cutting knives turn downwardly. In the downward position the lower cutting knife 58 has moved outwardly from the path of travel of the core shaft and core, and a core may move upwardly and into the space between the disks 58. As the core shaft moves upwardly, an annular bearing 88, which may be rigidly or rotatably mounted upon the core shaft 43, engages an arm or lever 89 which is locked to the shaft 54. As the core shaft 43 moves upwardly, the bearing 88 moves the lever 89 upwardly, which in turn pivots the shaft 54 within the supports 55. The core cutting assemblies 46 therefore move upwardly and into the cutting position. Upon the next movement of the turret, the shaft 43 is moved inwardly and upwardly through another arc, while the bearing 88 through engagement with the lever 89 pivots the shaft 54 which in turn moves the upper cutting disk 58 out of the path of travel of the core and shaft. When the core and shaft have moved beyond the upper cutting disk 58, the bearing 88 moves free of the lever 89 and the core cutting structures move downwardly and into a position to receive the next shaft and core. A suitable stop may be provided to limit the pivotal movement of the shaft 54, etc., such as 89a (Fig. 2).

In moving from the station c to the station d, the cores engage glue applicators or wheels 47. The glue applicators can be seen in Figs. 1, 2 and 3, while the detail of the arrangement is seen best in Fig. 5. A casing 90 providing a reservoir for a suitable glue is shown mounted upon a supporting bracket 91 which in turn is rigidly secured to a stationary tube 92. A cover 93 having a handle 94 closes the casing 90. The cover 93 has a plurality of longitudinally-spaced slots 95 through which extend the upper edges of the knurled applicator wheels 47. The wheels 47 are mounted upon a shaft 96 which is driven by means later described. As the applicator wheels 47 rotate within the reservoir provided by the casing 90, the knurled peripheries of the wheels pick up a quantity of glue which is applied to the surface of the core segments as the core moves over the wheels. 60 Any desired number of applicator wheels may be mounted upon the shaft 96 and it has been found particularly desirable to have two applicator wheels for each core segment when the segments are cut in lengths adapted for the winding of toilet paper.

When the winding of a core has been completed, the turret 44 continues to rotate and brings the wound core into the stripping position f and the stripper J removes the wound cores from the core shaft. The stripper J is seen best in Figs. 1 and 2 and in partial cross section in Figs. 3 and 5. The stripper J comprises a pair of pulley wheels 97 and 98 which are rotatably supported by support plates 99 and 100. A continuous belt 101 is mounted on the pulley wheels 97 and 98 and is moved thereby. Pulley wheel 98 is an idler wheel, while the pulley wheel 97 is driven by a motor 102 through a

belt 103. For this purpose, the armature shaft of motor 102 is equipped with a pulley wheel, if a belt is used as a driving connection, or the armature shaft may be equipped with a sprocket 104, and in this case the member 103 would be a link or sprocket chain. The axle 105 supporting the pulley wheel 97 between the supports 99 and 100 is equipped at one end with a pulley wheel or sprocket 106, as the case may be, which is driven by the belt or chain 103. The support plates 99 and 100 may be secured to the end frames or walls B and C by any suitable means, and in the illustration the plate 100 is mounted upon brackets 107 and 108 by any suitable means such as welding, while the brackets are secured to the end walls or frames B and C by bolts 109. Any suitable mounting for the motor 102 may be used.

The continuous belt 101 may be made of various materials, and it has been found that a leather belt gives very desirable performance. The belt 101 is equipped with a laterally-extending cleat or lug 110 that engages the wound core at the end adjacent the turret 44, and as the lug is moved from the left to the right of the machine by the rotational movement of the belt 101, the lug pushes the wound core from the mandrel or core shaft 43 and onto the upper surface of the belt 101. The cores are thus stripped from the core shafts and are delivered by the belt to a conveyor arrangement (not shown) or into packing boxes, etc., or otherwise removed from the machine. The upper half of the belt 101 is supported by an elongated member or supporting guide over which the belt glides. The elongated supporting guide 111 prevents the belt from sagging under the weight of the wound cores. An idler roller 112 mounted between the supporting plates 99 and 100 may be employed to take up slack in the belt. The actuation of the motor 102 which drives the stripper belt 101 at the proper time will be later described. The electrical circuit for the motor 102 is broken when the lug 110 trips a limit-switch 113 which is mounted under the lower half of the belt 101. In the position shown in Fig. 2, the motor 102 would be actuated and the stripper belt would be moving, because the lug 110 has not yet triggered the limit-switch 113. As the lug or cleat 110 moves toward the left of the machine, the limit-switch 113 would be triggered and the motor 102 would be deactivated, thus stopping the movement of the belt.

The turret 44 upon which are mounted the six spaced core shafts 43 comprises a pair of complementary spiders 114 and 115 which are keyed to the rotatably-mounted turret shaft 117 and held against axial movement by pins or set screws 116 (seen best in Fig. 7). If desired, the spiders may further be coupled by studs or bolts 116a extending therethrough (Figs. 3 and 5). The turret shaft 117 is rotatably mounted within the hangers or brackets 45 and a bronze or similar bearing 117a is provided in the hanger at the right end for this purpose (Fig. 8). If desired, a similar bearing may be included in the left end hanger. The shaft 117 is held within the hangers 45 by bolts 117b tightened against washers 117c. The spiders 114 and 115 are spaced apart and the core shafts or mandrels 43 are rotatably mounted within the spiders upon support bearings 118. The core shafts 43 are relatively heavy, particularly when loaded, and the spaced spiders 114 and 115 stabilize the shafts 43 by supporting them at two spaced points. A bushing 119 is fixedly mounted upon the portions of the shafts 43 that extend through the spiders 114 and 115, and the bearings 118 are mounted upon the bushings. Essentially, the shafts 43 are rotatably mounted within the spiders 114 and 115 and are driven in rotation during the winding of the web upon the cores at station e and for short periods before a shaft enters this station and for a short period after leaving, by a pulley wheel 120 which engages one side of the double V belt 48. However, the pulley wheel 120 is not directly fixed to the shaft 43 or to the bushing 119 but is rotatably supported thereon by spaced bearings 15

121, and a clutch assembly is provided to drive the shafts through the pulley wheels 120. The clutch functions to permit a gradual slowing-down of the core shaft as the roll builds up in diameter, the slip in the clutch increasing as this takes place. The clutch also prevents damage to the machine in the event that a core shaft becomes jammed, etc., and also eliminates shock, etc., in that the inertia of the core shaft is overcome gradually.

The pulley wheel 120 is equipped with a laterally-extending flange 122 that frictionally engages the flange 123 of a collar 124 through a friction plate 125. The collar 124 is keyed to the bushing 119 and is free to move axially thereon, and the bushing in turn is pinned or keyed or otherwise locked to the core shaft 43 and has a thrust bearing 126 mounted upon the periphery thereof. The outer race of the bearing 126 is equipped with a plurality of spaced pins or studs 127 extending into aligned apertures 127a provided in a nut 128. Springs 128a are positioned within the apertures 127a and urge the pins 127 and bearing 126 outwardly and against a shoulder with which the collar 124 is equipped. The nut 128 receives an externally-threaded sleeve 129 which in turn is received within the spider 115. The bearing 118 within the spider 115 is received within the sleeve 129. The nut 128 may be positioned to adjust the clutch initially by compressing the springs 128a as desired and allows compensation to be made for wearing, etc., of the friction plate 125. The bushing 119 is equipped at its inner end with a flange or clamp collar 130 that positions the bushing 119 within the spiders. The opposite end of the bushing 119 is also provided with a flange or clamp collar 131. The collars are split as are the ends of the bushing 119, and when the clamp collars are in position they lock the bushing and shaft 43 in position. 30 Further, the collars 130 and 131 are equipped with inwardly projecting extensions that engage the races of the bearings 118. The annular bearing or core cutter control bearing 88 previously discussed is mounted upon the end of the shaft 43 and is held in position by a lock or snap washer 132 and rotates freely when engaged by the lever 89. The shaft assembly is assembled and held with the spiders by removable caps 133 (seen more clearly in Figs. 1 and 2).

In the core cutting and web rewinding machine of 45 our invention, we desire to rotate the turret 44 intermittently so that each core shaft remains at each station for a short, predetermined length of time before it is moved on to the succeeding station. For this purpose, I equip the turret 44 with a mandrel driving assembly G 50 of a type that rotates the turret intermittently to move the mandrels through spaced arcuate distances. Specifically, I employ an internal Geneva movement that moves the core shafts 43 through all of the various stations while locking the turret so that the shafts are held for a definite time at each of the stations. The Geneva driving assembly consists of a generally circular plate or wheel 134 equipped with integral bosses 135 having threaded bores therein to threadedly receive bolts 136 extending through bores in the outer spider 115. The plate 134 is thereby 55 secured to the spider 115 and causes it to rotate when the plate 134 is rotatably driven. The plate 134 is equipped with a central bore 137 that receives the turret shaft 117. The Geneva driven member or plate 134 is equipped with six openings or bores 138 having their 60 centers equally spaced about an arc having its center on the rotational axis of the plate. Secured to the plate 134 and extending about each of the bores 138 is a generally U-shaped member 139 having an arcuate opening 139a therein that is somewhat less than a complete circle and is open on the side adjacent the axis of the plate. The arcuate opening is aligned with the bores 138. The members 139 form extensions of the plate 134 about the outer portion of each of the bores 138. The outer edges of the members 139 are straight and are machined 65 so that each pair of adjacent members 139 form elongated

slots 140 therebetween that are closed on one side by the plate 134 and that are open on both ends and also on the side that is away from the plate 134. The members 139 form six slots 140 and these slots fall on diameters of the plate 134 so that three pairs of diametrically opposed slots are formed.

The plate 134 is driven by a Geneva cam or driving member 141 which is provided with a central bore 142 that receives a rotatably mounted stub shaft 143. The driving member 141 is keyed to the shaft 143 which is journaled within the hanger or bracket 45 upon bearings 144. The stub shaft 143 extends through a plate 145 which is mounted upon the hanger 45, and the shaft 143 is journaled within the plate 145 upon bearings 146. The driving member 141 has a generally circular periphery which is indented at one point to form a cam 147 (seen best in Fig. 6). The driving member 141 is also equipped with a roller or driving wheel 148. A crescent-shaped locking member 149 is mounted upon the inner surface of the driving member 141 and is diametrically opposed to driving roller 148. It is preferred that the locking member 149 be formed integrally with the driving member 141, but it may be a separate member secured to the driving member 141 by any suitable means such as welding. The driving wheel 148 is mounted upon the driving member 141 by means of a stud and lock nut 150.

The driving member 141 is mounted so that the driving wheel 148 engages the slots 140 while the locking member 149 rotates within the extensions of the bores 138 formed by the plates 139. The driving member 141 does not move relative to the center of the Geneva plate 134 but is driven in rotation by the shaft 143 by means later described. Following a sequence of operations, as the member 141 rotates, the driving wheel 148 enters the inner end of the slot 140 and as the driving member 141 rotates, the wheel 148 moves outwardly through the slot 140, and in so doing, rotates the driven member or plate 134. The driving wheel 148 moves through slot 140 to its outer end and then returns through the slot and finally leaves the inner end. During the movement of the driving wheel 148 within the slot 140, the driven member or plate 134 is moved through one-sixth of a complete rotation. While the driving wheel 148 has moved outwardly and has then returned through slot 140, the crescent-shaped locking member 149 has been moving outside of the partial bore formed by the member 139. When the driving wheel 148 has completed a movement into a slot 140 and has left the slot after the plate 134 has been rotated one-sixth of a complete rotation, the locking member 149 enters the extension of the bore 138 formed by the member 139 and locks the Geneva driven member 134, and consequently the turret to which it is secured, against rotational movement. The locking member 149 escapes from the bore extension provided with the member 139 when the driving wheel 148 has moved from the inner end of the slot 140 and has rotated to a position in which the wheel is entering the next slot 140. It is seen, then, that the turret 44 and the core shafts 43 mounted therein are rotated through a sixth of a revolution and are then locked in position while the locking member 149 is within the extension of the bore 138, and the turret is then moved through another sixth of a revolution by the action of the driving wheel 148 within a slot 140 while the locking member 149 is free from or has escaped from the extension 139a of the bore 138.

The turret 44 and the Geneva driving assembly are mounted upon the depending hanger or bracket 45 that is adjacent the left end wall B of the machine. This bracket as well as the bracket 45 depending on the opposite end of the machine are pivotally or rockably mounted upon the upper tubing E. For this purpose, the upper ends of the brackets 45 form a semicylindrical bearing to which is secured a mating cap 151 which may be secured to the end of the bracket 45 by bolts in any well known manner. It is desired to have the brackets 45 held within a position

such that a core shaft which is in the position to start winding is generally abutting the bed roll 28. To insure this positioning of the brackets 45, a counterweight 152 is attached to the bracket 45 that is adjacent the left end of the machine. The force exerted by the counterweight 152 is sufficient to urge the turret, etc., rearwardly and the core shaft which is in the web winding position abuts the bed roll 28. However, it is desired to provide a sufficient clearance between the bed roll and the core shaft to permit a length of webbing to be wound upon the core to form a relatively heavy roll. To provide this clearance, a roller 153 (seen in Fig. 4) is rotatably mounted upon an axle attached to a forwardly-extending bracket 153a secured to the end wall B. The periphery of the Geneva driving member 141, which is mounted on the hanger 45, engages the roller 153, and the positioning of the roller 153 is such that the brackets 45, and consequently the core shaft which is in web winding position, are normally held in spaced-apart relation with the bed roll 28. However, when the cam 147 in the periphery of the Geneva driving member 141 rotates to a position receiving the roller 153, the counterweight 152 forces the turret assembly, etc., to pivot inwardly and the core shaft abuts the bed roll. This occurs once during each rotation of the Geneva driving member 141, and the cam is positioned so that the inward swinging of the brackets 45, etc., occurs when a core shaft is moving into the web winding position. A core mounted upon the shaft, and which has already had glue applied to the periphery thereof, is thereby forced into contact with the end of the web and the web adheres thereto. As the Geneva driving member 141 continues to rotate, the cam 147 moves out of engagement with the roller 153 and the core shaft is moved outwardly from the bed roll 28 and is ready to have a substantial length of webbing wound thereon without interference.

The driving mechanism for our machine will now be described, with particular reference to Fig. 6. A motor 154 is mounted within the frame A in any well known manner and is used to drive a clutch assembly 155 through a multiple belt 156 driven by a pulley wheel 157 attached to the armature shaft of the motor. Any conventional clutch 155 may be used and since these are well known in the art, a detailed description will not be given. The clutch 155 is actuated from any one of a number of positions in the front of the machine by levers 158 (seen in Fig. 1) which are locked to a rock rod 159 which is pivotally mounted within the brackets 107 and 108. The rod 159 is coupled through a link 160 and arm 161 to the clutch actuating member 155a. Movement of the levers 158 serves to engage and disengage the clutch 155. The clutch 155 is also equipped with a hand wheel 162 that permits the driving shaft to be operated manually when this is desired. A limit or stop rod and arm 162a actuate a brake when the levers 158 are in forward position. If desired, a safety switch 162b may be positioned to break the motor circuit upon appropriate movement of the levers 158.

A drive shaft 163 is mounted within the clutch 155 and is driven in rotation by the motor 154 when the clutch is engaged. The opposite end of the drive shaft 163 is equipped with a spur gear 164 which drives a gear 165 mounted upon the end of the axle 166 upon which the bed roll 28 is mounted, and the bed roll is thereby rotated. Mounted upon the axle 166 adjacent the gear 165 is a pulley wheel 167 which drives a sheave or pulley wheel 168 secured to the axle of the delivery roller 16. An idler roller 169 is provided to take up slack in the pulley belt 170 which links the wheels 167 and 168.

The gear 165 secured to the bed roll axle 166 drives a spur gear 171 which is mounted upon the axle of the web slitting roll 25. The opposite end of the web slitting roll axle is provided with a gear 172 that drives a spur gear 173 through idler gears 174 and 175. The spur gear 173 is mounted upon the web slitting shaft 27 which

drives the slitting knives 26. The gear 171 rotates the secondary perforator roll 21 by engagement with the gear 176 which is secured to the axle of the secondary perforator roll.

Mounted upon the opposite end of the axle of the secondary perforator roll 21 is a spur gear 177 which meshes with a gear 178 mounted upon the axle of the perforator roll 22 and the roll 22 is thereby driven. At the same time, the gear 177 engages gear 178 mounted upon the axle of the feed or pull roller 20. Mounted upon the pull roller axle and adjacent the gear 179 is a sprocket 180 which drives a second sprocket wheel 181 through a sprocket chain 182. Idler sprockets 183 and 184 take up slack in the sprocket chain 182. The sprocket wheel 181 is equipped with a short axle 185 upon which is mounted a worm gear 186. The worm gear 186 engages and drives worm wheel 187 which in turn rotates a worm wheel 188 which is secured to the common axle 189. The worm wheel 188 drives worm 190 which is mounted upon a common axle 191 with a spur gear 192. Rotation of the worm 190 thereby rotates the spur gear 192 and it in turn meshes with idler gear 193 which drives a timing gear 194.

The timing gear 194 is mounted upon an axle 195 which is equipped at one end with a hand wheel 196 and upon the opposite end with a spur gear 197. The spur gear 197 rotates an idler gear 198 which in turn drives the Geneva driving gear 199 which is mounted upon the stub shaft 143 to which the Geneva driving member 141 is secured.

The core shafts or mandrels 43 are rotated when in the web winding position by the double V belt 48 which engages the pulley wheels 120 that are mounted upon the core shafts 43. The belt 48 is driven by a large pulley wheel 200 which is mounted upon the drive shaft 163. A pair of idler pulley wheels 201 and 202 complete the circuit for the belt 48. It can be seen in Fig. 3 that the idler pulley wheel 202 is rotatably mounted upon one arm of a bell crank 203 which pivots upon a shaft 204. A counterweight 205 is mounted upon the opposite arm of the bell crank 203 and tends to pivot the bell crank in a direction in which slack in the belt 48 is taken up by the idler wheel 202.

The driven backing roller 86 which rotates the cores during the core cutting operation at station b is continuously driven by a separate driving motor 206 which is coupled to the backing roller through a gear reducer 207, spur gear 208 and 209, and a driving rod 210 which is directly coupled to the roller 86 by a universal joint 211. The backing roller 86 is equipped at its opposite end with a sprocket 212 (seen in Fig. 5) which drives a second sprocket 213 through a sprocket chain 214. Mounted upon the same axle with the sprocket 13 and adjacent thereto is a larger sprocket 215 which drives the shaft 96 upon which the glue applicator wheels 47 are mounted through a sprocket chain 216 which engages a sprocket 217 mounted upon the end of the shaft 96. Both the backing roller 86 and the glue applicator wheels 47 are continuously driven, then, by the motor 206. The sprockets 213 and 215 are both rotatably mounted upon a bracket 218 which is fastened by screws or any other suitable means to a brace 219 which in turn is mounted upon the stationary tube 92 and which rotatably supports the backing roller 86.

The stripping conveyor or belt 101 is driven by an independent driving motor 102. Since the driving assembly for the stripper has previously been discussed, it will not now be further mentioned.

Referring particularly to Fig. 9, which shows more clearly the mounting of the timing gear 194 and the Geneva driving gear 199, the means by which the machine is timed will be explained. The spur gear 197 is keyed to the axle 195 and is locked against axial movement thereon by a pin or set screw 220. The axle 195 is rotatably supported upon bearings 221 within the upper tubing E. The bearings 221 are locked upon the axle 195 by a nut

222 which receives the threaded end of the axle 195. A bushing assembly, etc., of the well known type is further employed in conjunction with the bearing 221 and the axle 195 to rotatably secure the axle within the tubing E. The opposite end of the axle 195 is reduced in diameter and equipped with a plurality of keys and keyways 223 upon which the hand wheel 196 and the timing gear 194 are splined. The hand wheel 196 and the timing gear 194 are locked together by bolts 224 so that axial or sliding movement of the hand wheel upon the splined portion of the axle 195 also moves the timing gear 194. A washer 225 and lock nut 226 with which the splined end of the axle is equipped prevent unintentional movement of the hand wheel 196 and the timing gear 194 attached thereto, from the axle 195.

The slideable movement of the hand wheel 196 and the timing gear 194 becomes important in the event that the web 15 being fed through the machine is accidentally broken in some manner. When this occurs, a great waste of paper would result if it were necessary to detach the broken web and rewind a portion of it upon either the core that is within the web winding position, or to wind a portion upon a new core, so that the machine could continue through a normal sequence of operations before again being ready to rewind a complete and usable roll of paper. If breakage occurs, it is only necessary to withdraw the hand wheel 196 which in turn disengages the gear 194 from the idler gear 193. The gear train is then broken and the Geneva drive, etc., are no longer linked with the prior gears and movements of the machine. Since the hand wheel 196 is splined to the axle 195, the axle and the spur gear 197 may be rotated by manual movement of the hand wheel and in this manner the Geneva drive is actuated and a new core is moved into the web winding position. When the web is then attached to the core, a complete roll of paper may be wound upon the core and the only wastage is the length of webbing that was being wound upon the previous core when the breakage occurred.

Due to the fact that each tooth on the change gear 194 represents one revolution on bed roll 28, the machine cannot get out of time when the Geneva drive has been operated manually.

It may be that it is necessary from time to time to adjust our web rewinding machine to permit rolls of various sizes to be wound. For example, it may be desired at one time to wind rolls of toilet tissue having 650 sheets per roll, while at another time rolls having 1,000 sheets thereon are required. Changing the machine for this purpose is readily accomplished by removing the lock nut 226 and the washer 225 from the splined end of the axle 195 and then withdrawing the hand wheel 196 and the timing gear 194. The bolts 224 are removed and the timing gear 194 is free of the hand wheel 196. The timing gear 194 may then be replaced with another timing gear of greater or less diameter, depending upon whether it is desired to rotate the turret more slowly so that larger rolls of paper may be wound, or to rotate it more rapidly so that smaller rolls are wound. The new timing gear is then secured in position upon the hand wheel 196 by the bolts 224 and the assembled unit is replaced upon the splined end of the axle 195. The washer 225 and the lock nut 226 are then replaced and the machine is ready for operation.

By referring to Fig. 4 and Fig. 9, it will be seen that provision has been made for interchanging the timing gears 194 by mounting the idler gear 193 which drives the timing gear 194 upon a laterally movable axis. The gear 193 is rotatably mounted upon a stud 227 equipped with bearings 228. The stud 227 is mounted for lateral movement within an arcuate slot 229 and is locked within the slot at a selected position by an elongated nut 230 and a hexagonal member 231 formed integrally with the stud 227. As the stud is screwed into the nut 230, the member 231 is drawn tightly against the frame A. The outer end of the stud 227 is threaded and receives a nut

232 that retains the bearings 228 and the gear 193 upon the stud.

It may be seen in Fig. 9 that the gear 192 is secured to the shaft 191 by a set screw 232 and that the idler gear 198 is mounted upon an axle 233 equipped with bearings 234 and which is mounted upon the bracket 45.

The ease with which the apparatus may be timed is largely facilitated by the actuating mechanism we employ to start the core stripping motor 102 and to trigger the web severing knife 235 (seen in Fig. 3 and in detail in Figs. 10 and 11) and which will later be described. The core stripping motor 102 is actuated by a limit-switch 236 which is mounted upon the plate or bracket 145 (Figs. 12 and 13). The limit-switch 236 may be secured to the plate 145 in any suitable manner and for this purpose we prefer to mount the switch upon a bracket 237 equipped with elongated slots 238 and which may be mounted upon the plate 145 by screws 239 extending through the slots 238. The slots 238 permit the bracket 237 to be adjustably positioned upon the plate so that it may be actuated at the proper instant. The limit-switch 236 is secured to the opposite end of the bracket 237 by any suitable means such as screws, etc., and is equipped with the usual biasing spring 240 and actuating lever 241. We prefer to equip the outer end of the lever 241 with a roller 242. The limit-switch 236 is actuated when an arm 243 which is mounted upon the end of the stub shaft 143 and rotates therewith engages the roller 242. The arm 243 may be secured to the end of the stub shaft 143 in any desired manner, and in the illustration the arm 243 is slotted so that the ends may be drawn tightly about the end of the shaft by a bolt, etc. The arm 243 makes one revolution for each complete revolution of the Geneva driving member 141, and it is seen that the switch 236 and consequently the stripper motor 102 will be actuated once for each revolution of the Geneva driving member. This occurs, as previously explained, once for each one-sixth of a rotation of the turret 44 or once each time a new core and shaft is moved into the stripping position.

Mounted upon the opposite upper corner of the plate 145 is a second limit-switch 244. The limit-switch 244 is secured to a brace 245 by any suitable means, and the brace in turn is mounted upon the plate by screws 246. The limit-switch 244 is equipped with a biasing spring 247 and arm 248, the outer end of which is provided with a roller 249. Upward movement of the arm 248 triggers the limit-switch 244 and causes the web severing knife 235 to sever the web.

The switch 244 is actuated when the arm 243 engages a shoulder 250 with which a lever 251 is equipped. The lever 251 is pivotally mounted upon a bolt 252 equipped with a bearing washer 253. The arm 243 is restrained from axial movement on the bolt 252 by a lock nut 254. The lever 251 is normally biased against a stop 255 by a spring 256, and movement of the arm 243 against the shoulder 250 moves the end of the lever to which the spring 256 is secured in a manner to extend the spring.

Upon the upper end of the lever an actuating block 257 is pivotally mounted. The block 257 is equipped with a straight, angular edge 258 which is held in normal engagement with a mating edge provided in the lever 251 by a spring 259. When the arm 243 engages the shoulder 250, the upper end of the lever 251 is pivoted to the right, in the illustration in Fig. 12. As the block 257 is moved against the roller 249, when the upper end of the lever 251 is moved to the right, the block is pivoted and slides under the roller 249 without actuating the limit-switch 244. However, when the arm 243 has moved past engagement with the shoulder 250, which is cut off very sharply at its lower end, the action of the spring 259 snaps the lever 251 back into its normal position against the stop 255. In the meantime, when the block 257 had moved beyond or to the right of the roller 249, the action of the spring 259 returned the block to its normal position (the one shown in Fig. 12).

Since the block can pivot no further in the direction in which it is biased by the spring 259, when the lever 251 returns to its normal position the upper corner of the block 257 engages the roller 249 and forces the roller 5 and the arm 248 upwardly and the limit-switch 244 is actuated. It is seen that this assembly provides an extremely rapid and singular actuation of the limit-switch 244 which is particularly desirable since the actuation of the web severing knife must be extremely quick and must 10 occur at the proper time. It is apparent that the web severing limit-switch 244 is actuated once for each rotation of the arm 243. The plate 145 is secured to the left hanger 45 in spaced-apart relation by spacers 159a centrally bored to receive bolts.

While the web is being wound upon cores received by the mandrels 43, it is necessary to lock the cores to the mandrels so that they rotate when the mandrels or core shafts 43 are being driven by the belt 48. The locking mechanism can be seen best in Fig. 7. The core shafts 43 are hollow throughout their length and support concentrically therein a rod 260. The rod 260 is slidable axially within the core shafts and for this purpose is slidably supported in bearings 261 and 262. The bearings may be of bronze or any other suitable material and may be secured 15 within the ends of the core shafts 43 in any well known manner such as by pressing the bearings into the ends. The slidable rod 260 is equipped with a cone-shaped guide 20 and supporting member 263 at the end adjacent the free end of the core shaft. The slidable rod is equipped with 25 a collar 265 that is pinned to the rod to prevent axial movement of the stop with respect to the rod. A stop 266 is pinned to the rod adjacent the bearing 261 and prevents the rod from being withdrawn from the core shaft. A helical spring 267 is interposed between the bearing 262 30 and the collar 265 and normally urges the rod 260 axially toward the free end of the core shaft.

The core shafts are equipped with a plurality of axially-spaced slots 268 that are alternately on opposite sides of the shaft. Adjacent each of the spaced slots 268, the 35 slidable rod 260 is provided with dogs or locking fingers 269. The fingers 269 are received within elongated recesses 270 within the rod and are pinned within the recesses so that they may be pivoted or rocked. The outer end of the fingers 269 is received within the slots 268 and when the slidable rod 260 is moved to its extreme right 40 position or when the stop 266 is abutting the bearing 261, the upper edge of the dogs or fingers lies flush with the outer surface of the core shafts 43. In this position, cores may be inserted onto the core shafts or may be freely withdrawn therefrom. When the rod 260 is moved toward 45 the left against the force exerted by the spring 267, the fingers 269 pivot within the recesses provided in the rod 260 and the upper edge of the fingers juts outwardly from the slots 268 and from the surface of the core shaft. In 50 this position the fingers engage the inner surface of the cores mounted upon the shaft and the cores are so locked that relative rotational movement between the cores and shaft is prevented. It has been found satisfactory to employ one locking finger 269 for each core segment when 55 rolls of toilet paper are being wound.

60 The means by which the locking fingers 269 are actuated through movement of the rod 260 against the force of the spring 267 may best be understood by referring to the structure illustrated in Fig. 8. The rod 260 is moved axially within the core shaft to the finger-locking position 65 by an arm 271. The arms 271 are equipped at their outer end with a cup 272 in which a bearing 273 is supported. Secured to the inner race of the bearing 273 is a cone 274 adapted to receive the pointed or coned end of the member 263. Since projection of the locking fingers 269 through the slots within the surface of the core shafts results in the slidable rod 262 rotating with the core shaft, the bearing assembly in the cup of the arm 271 permits the rod and core shaft to be rotatably supported therein.

The arms 271 are pivotally mounted upon a spool-shaped member 275 which is equipped with a bore 276

adapted to receive the turret shaft 117. The member 275 is locked to the shaft 117 by a set screw 277. The spool-shaped member 271 has a laterally-extending flange 278 at one end upon which the arms 271 are pivotally mounted and a laterally-extending flange 279 at its opposite end to which links 280 are pivotally secured. A connecting link 281 is pivotally fastened to both the arm 271 and the link 280 and has an extension 282 to which a roller 283 is fastened by means of a bolt 284 and a nut 285. The link 280, connecting link 281 and roller 283 constitute a cam follower and pivot the arm 271 about its mounting upon the spool-shaped member 275. A barrel cam 286 is secured to the depending hanger 45 by bolts 287. The cam 286 is provided with a bore 288 adapted to receive the turret shaft 117. The periphery of the cam 286 is equipped with a groove or channel 289 that receives the rollers 283. The shape of the channel 289 is such that the arms 271 are moved into a position of engagement with the coned ends 263 of the slidable rods 260 during certain positions of the core shaft while the arms are withdrawn from engagement with the ends of the slidable rods 260 and into a retracted position during other positions of the core shafts. The retracted position of the arm 271 is indicated by the lower arm shown in Fig. 8 and is designated by the number 271a. An arm 271 is provided for each core shaft 43 and the arms move into engagement with their respective core shafts when the shafts are generally adjacent the glue applicator wheels 47 and retract when the shafts move from the web winding position.

It has been found that the coned ends 263 of the slidable rods will not always move into seating position within the cones 274 as the arms 271 are pivoted into engagement with the rod ends. To insure seating and thereby prevent damage, etc., to the parts, the outer ends of the arms 271 are also equipped with U-shaped or fork-shaped members 290. The U-shaped members 290 have spaced prongs 291 that receive the cone-shaped outer end 263 of the rods 260 and guide them into position within the cones 274. When the members 263 are firmly seated within the cones 274, the ends 263 are moved beyond the point of engagement with the prongs 291 and rotate free of the prongs.

Not only must the arms 271 be withdrawn from the position supporting the core shafts 43 when the cores are inserted onto and withdrawn from the shafts, but it is also essential that the arms be retracted into position permitting movement of the arms under the bracket 292 which supports the stationary tube 92. As mentioned previously, the tube 92 is utilized as a means for supporting the glue applicator assembly and also supports the driven roller 86 which rotates the cores when at the core cutting station. Bracket 292 is rigidly secured to the hanger 45 by bolts 293.

After a predetermined length of webbing has been wound upon the cores, the wound length of webbing is severed from the continuous webbing strip 15 which is drawn from the parent roll 10. The turret 44 then rotates the filled core through an arcuate distance to the core stripping station *f*, and at the same time a partially filled core is moved into the web winding station *e*. The severing knife 235 is mounted within the bed roll 28 and is actuated periodically to sever the web at the proper instant. The actuating assembly is shown most clearly in Figs. 10 and 11, and reference will be made to these figures in describing the features of this assembly. Rotatably mounted upon the bed roll axle 166 is a spool-shaped member 294 having a central cylindrical portion 295 equipped with laterally-extending flanges 296 and 297. The flange 297 is provided with apertures 298 which receive bolts (not shown) which rigidly secure the spool-shaped member 294 to the end wall C of the machine. The flange 296 has a continuous circular periphery with the exception of a slot 299 cut in one portion of the flange. The slot 299 is adapted to receive selectively a cam member 300 or a filling block member 301 which completes the periphery of the flange and makes it a complete circle throughout. The cam 300 and the filling block member 301 are

mounted upon a rod 302 that extends between the flanges 296 and 297 and slightly beyond the flange 296. The rod 302 is slidably mounted within a laterally-extending support 303 which is formed integrally with the cylindrical portion 295 of the spool-shaped member. The cam 300 and the filling block member 301 are locked to the slidable rod 302 by any suitable and well known means so that these members move with the rod. Two spaced washers 304 are rigidly fastened to the slidable rod 302 and provide a stop or support surface against which a helical spring 305 abuts on one end, while the opposite end of the spring is positioned against the inner surface of the flange 297. The force exerted by the spring 305 against the flange 297 and the washers 304 normally forces the slidable rod 302 to move toward the left or toward the bed roll 28 to a position in which the cam 300 is received within the slot 299 provided in the spool flange 296. The cam 300 is held within the slot 299 with its side walls lying flush with the side walls of the flange 296 by proper positioning of the stop washer 304. The washer 304 engages the integral support 303 and limits the axial movement of the rod 302 toward the bed roll 28. The rod 302 is normally held in a position in which the filling block member 301 lies within the recess or slot 299 and completes the periphery of the flange 296 by a stop finger 306 which enters a notch 307 in the lower surface of the slidable rod 302. The notch 307 is positioned so that when the stop finger 306 enters therein the filling block member 301 makes a perfect completion of the periphery of the flange 296.

The stop finger 306 slides within a recess 308 with which the integral support member 303 is equipped. Secured to the lower end of the stop finger 306 is the armature 309 of a solenoid 310. Solenoid 310 is mounted upon a bracket 311 which in turn is rigidly secured to the support member 303 or to the surface of the cylindrical member 295 by welding, etc. When the solenoid 310 is actuated, the armature 309 is drawn downwardly and the stop finger 306 is moved out of notch 307, and the force of the spring 305 moves the slidable rod 302 and the cam 300 secured thereto to the left and the cam replaces the filling block 301 within the slot 299. The solenoid 310 is actuated by the limit-switch 244 (Figs. 12 and 13) once for each movement of the turret 44, in the manner previously described. Thus, when the limit-switch 244 is tripped, the solenoid 310 is actuated and the slidable rod 302 moves the cam 300 into the slot 299.

A cam follower 312 comprising a slotted link 313 equipped with a rotatably mounted roller 314 and a shaft 315 actuates the web severing knife 235 in response to the indentation in the periphery of the flange 296 caused by the cam 300. The link 313 is locked to the shaft 315 which in turn is pivotally mounted within the bed roll 28, and the roller 314 is held in engagement or rides upon the periphery of the flange 296 by the force exerted by spring members 316 against arms 317 which are locked to the shaft 315. The shaft 315 is equipped with a plurality of arms 317 which hold or support the web severing knife 235. The knife 235 may be bolted or welded, etc., to the arms 317. A spring 316 is provided for each of the arms 317 and the springs are supported within recesses provided in a support member 318 mounted within the bed roll 28. In Fig. 11, the severing knife 235 is shown within the bed roll 28 as solid lines and the position of the severing knife when it is actuated is shown by dotted lines and indicated by the number 235a.

On the severing knife 235 are mounted elliptical guide members 320. The guides may be bolted or riveted, etc., to the knife 235. When the severing knife is actuated, both the knife and the guide members 320 move laterally and outwardly from the surface of the bed roll 28 through an elongated slot 321 extending from end to end of the bed roll. The slot 321 is equipped with spaced, laterally-extending slots or openings 322 through which the guide members 320 project. The guides 320 engage

the web 15 and force it outwardly from the surface of the bed roll 28, thereby tensioning the web slightly and the severing of the web is facilitated. Not only does the tensioning of the web aid penetration and cutting of the web by the serrated knife 235, but it also serves to break any uncut portions not completely severed by the knife.

The guide members 320 perform the important additional function of pushing the severed leading edge of the web 15 away from the peripheral surface of the bed roll 28 so that it does not cling thereto and also avoids any possibility of the web's being drawn into the slot 321 by the return movement of the severing knife 235. The guides also actively urge the leading edge of the web into contact with the glue-equipped core segments being moved into the winding position and thereby accommodate the adherence of the web to the core segments. The guides 320 may be made of any suitable material such as metal, plastic, or relatively stiff belting of fiber or rubber, etc.

After the web has been severed, it is necessary to move the cam 300 from the recess or slot 299 so that the filling block may again complete the periphery of the flange 296. For this purpose, the filling block 301 has formed integrally therewith a projection or cam follower 323 which engages a cam 324 mounted upon the end of the bed roll 28. As the bed roll 28 rotates, the cam 324 engages the cam follower 323, and the filling block 301, cam 300 and slidable rod 302 are moved to the right. The stop finger 306 moves into the notch 307, the solenoid 310 being deactuated, and the rod 302 is thereby locked in the position in which the filling block is within the recess or slot 299. The periphery of the flange 296 is thereby completed and the severing knife 235 is not again actuated until the solenoid 310 is energized by the tripping of the microswitch 244.

In Figs. 16 and 17 a detail of the web slitting knife assembly is illustrated. The web slitting knives 26 normally enter the annular grooves 325 with which the web slitting roll 25 is equipped. It is necessary, however, to withdraw the knives or disks 26 from the grooves 325 when a web is threaded through the machine. For this purpose, one end of the shaft 27 is equipped with a crank 326. The shaft 27 is rotatably mounted within the bore 327 provided in one end of the crank 326, but the crank is locked against axial movement with respect to the shaft 27. The opposite end of the crank 326 is equipped with a handle assembly 328 comprising a rod 329 rigidly secured within a bore 330 in the crank 326, a sleeve 331 equipped at one end with a laterally-extending flange 332 and at the opposite end with a cam surface 333, a collar 334 equipped with a lever 335 and having at one end a cam surface 336 which mates with the surface 333 and at the opposite end with a shoulder 337, and a stop member 338 providing an integral shoulder 339. The flange 332 is mounted upon the end frame or wall C of the machine by means of bolts extending through apertures 340 with which the flange is provided. The rod 329 is rotatable within the sleeve 331 and the collar 334, while the stop 338 is keyed to the end of the rod to prevent rotation with respect thereto. The stop may also be pinned to the rod to prevent axial movement of one with respect to the other when the stop member 338 is positioned on the end of the rod.

When assembled, the lever 335 may be moved clockwise, and this movement through engagement of the cam surfaces 333 and 336 moves the collar 334 axially or to the left with respect to the sleeve 331. During this movement the shoulder 337 of the collar 334 is in engagement with the inner surface of the stop member 338. Since this member is pinned and keyed to the rod 329, the rod 329, crank 326, and the shaft 27 and cutting disks 26 are all moved to the left. Continued movement of the lever 335 brings the shoulder 337 into engagement with the shoulder 339 with which the stop 338 is equipped, and the stop is rotated with the lever and the collar 334 to which it is secured. The crank 326 therefore pivots about the axis provided by the rod 329, and in so doing

moves the shaft 27 and the disks or cutting knives 26 attached thereto rearwardly and away from the web slitting roller 25. The surface of the roller 25 is thereby freed and a web 15 may be threaded freely through the machine.

It is not enough to simply pivot the shaft 27 and web slitting knives 26 rearwardly from the roller 25, because the cutting knives 26 are resiliently held in engagement with the edge 341 of the annular grooves 325 by the spring-like action of the knives 26 resulting from the particular mounting employed. The knives 26 are annular rings of spring steel secured to the flanges 342 of the supporting wheels 343 at a single point by the two spaced pins or rivets 344. The knives or rings 26 are free of the wheels 343 at all other points and normally tend to spring away from the flange 342 and into resilient engagement with the edge or shoulder 341 of the grooves 325. The wheels 343 are secured to the shaft 27 by pins 345. Movement of the lever 335 accomplishes lateral movement of the cutting knives or rings 26 from the edge of the grooves 325 and also moves the cutting knife assembly rearwardly from the surface of the slitting roll 25. To permit such movement, the opposite end of the shaft 27 is provided with a crank 346 (seen in Fig. 4) which is pivotally or rockably mounted upon the end frame or wall B by means of shaft 329 to which it is keyed. The shaft 329 is also normally forced to the right (Fig. 17) by means of springs recessed in end wall C acting against a thrust bearing on shaft 329 (not shown). A pawl 347a equipped with a handle (seen in Fig. 2) is engageable with a shoulder 347b on the periphery of the stop member 338 to hold the cutting knives 26 in spaced relation with the web slitting roll 25 when this is desired.

An adjustment is provided for controlling the pressure exerted by the feed roller 20 against the secondary perforator roll 21 and also for adjusting the engagement pressure between the perforator roll 22 and the secondary perforator roll 21. The adjusting means employed may be seen in Fig. 2, and the purpose of the adjustment is to determine the tension of the web 15. The adjustment constitutes a pair of bearings 348, one mounted in each of the end frames or walls B and C. The bearings are mounted in eccentric apertures or openings provided in the end frames, and the periphery of each of the bearings 348 is equipped with teeth. A pair of complementary pinion gears 349 are mounted upon the ends of a shaft extending across the machine and projecting outwardly through the end frames B and C. The pinions 349 are positioned to engage the teeth in the periphery of the eccentrically mounted bearings 348 so that rotating the pinions also rotates the bearings. The pinions 349 are equipped with a head 350 providing a fitting adapted to receive a wrench to facilitate turning of the pinion. A clamp 351 having a flange portion extending over the side of the bearings 348 is secured to the end frame C by bolts or cap screws. The screws may be tightened to bring the clamp 351 into frictional engagement with the bearing 348 mounted in the end frame C to lock it in any desired position. The pair of pinions 349 locked to a single shaft insures corresponding adjustment of the two bearings 348, since movement of one pinion moves the other, with the result that the feed roller 20 which is mounted within the bearings 348 is accurately aligned.

A similar pair of bearings 352, pinions 353 and a clamp 354 are provided for the axle or shaft of the perforator roller 22, and the pinions may be adjusted to rotate the bearings 352 to a position resulting in proper tensioning of the web 15.

In Fig. 2, switch and fuse boxes 355, 356 and 357 are shown mounted upon a panel 358 which is secured to the end frame C by appropriate bracket members. A similar switch and fuse box 359 is mounted upon the plate 100 by any suitable means such as screws or welding, etc., as is a switch 360. The boxes provide an accessible fusing means for the various motor circuits and may also include safety switches, start-stop switches, etc. The usual

fused motor circuits are employed, and a detailed description is therefore believed unnecessary. Light sockets 361 (seen in Fig. 1) are provided for the machine.

Operation

A parent roll 10 having a substantial quantity of webbing such as paper, etc., wound thereon, is mounted upon the brackets 12 with the ends of the axle or shaft 11 positioned within the elongated slots 13. The leading edge of the web 15 is drawn over the idler rollers 17 and 19 and is fed between the feed roller 20 and the secondary perforator roll 21, and then between the roller 21 and the perforator roll 22. The web is then brought around the roller 21 and is fed between this roller and the web slitting roller 25. The lever 335 is then thrown rearwardly to move the web slitting knives 26 from engagement with the roller 25. The web 15 is then brought between the slitting knives and the roller 25, around the roller 25 and between it and the bed roll 28. The web is then threaded between the bed roll 28 and the guide roller 29 which abuts the periphery of the bed roll 28. The lever 335 may then be returned to its normal position in which the slitting knives are in web slitting engagement with the roller 25. To facilitate threading the web 15 through the roller assemblies, the clutch 155 may be released and the hand wheel or drive shaft actuating member rotated, which will slowly turn the various rollers and thereby aid in the threading process. Alternatively, an experienced operator may be able to thread the webbing 15 through the roller assemblies while the main drive motor 154 is operating and the clutch 155 is engaged to rotate the various rollers. In either event, once the webbing 15 is threaded through the roller assemblies, the machine is ready for continuous operation.

If the threading operation has been completed while the machine was shut off, the main switches are now thrown to actuate the motors 154, 102 and 206. The roller 86, which rotates the cores when in the core cutting position, is thereby rotated and the glue applicator rollers 47 are rotated through the sprockets and chains previously described. The hand wheel 196 is moved outwardly from the end frame or wall B to disengage the timing gear 194 from the roller driving gear assembly, etc. The hand wheel 196 is then rotated to move a core over the glue applicator rollers 47 and, if desired, somewhat beyond this position. The hand wheel 196 is then moved inwardly toward the end frame B to engage the timing gear 194 with the idler gear 193, etc. The levers 158 are then thrown to actuate the clutch 155 and the whole gear train shown in Fig. 6 begins to operate. The Geneva drive member 141 continues to rotate the turret or spider assembly 44 and a core having glue applied to the periphery is moved into the web winding position. As the core and shaft are being moved into the web winding position, the pulley wheel 120 mounted upon the core shaft engages the double V belt 48 and the core shaft begins to rotate and is rotating at its normal velocity when completely moved into the web winding position. The leading edge of the web 15 which has been threaded through the machine is picked up by the rotating core and is stuck thereto by the glue.

The crescent-shaped locking member 149 mounted upon the Geneva drive member 141 is rotating within the extension of the bore 138 provided by the member 139 mounted upon the Geneva driving wheel 134. The Geneva wheel or driven plate member 134 is thereby locked against movement and the turret assembly 44 is thereby held in position and the core shafts are locked in their respective stations.

In moving over the glue applicators 47, the retractable core shaft supporting arm 271 moves into engagement with the cone-shaped end 263 of the slidable rod 260 and the core locking dogs or fingers 269 are moved outwardly and lock the core so that the core rotates with the shaft. When the core shaft 43 is then rotated by the belt 48

when in the web winding position, the individual core segments which are locked by the dogs 269 rotate with the core shaft and the webbing is wound into a roll upon the core.

As the web 15 is pulled through the machine by the feed roller 20, etc., and the bed roll 28 and guide roll 29, the web is slit into strips by the slitting knives 26. The width of the strips will correspond to the width of the individual core segments mounted upon the core shafts. The web is also perforated transversely by the action of the perforator knives 23 and the recesses 24 in the secondary perforator roll 21. When the web is delivered to the web winding position and is wound upon the individual core segments, it is slit into strips of the desired width and is also perforated to later facilitate tearing a portion of the paper from the wound roll by the consumer.

After a predetermined length of webbing has been wound upon the core to form rolls of paper, etc., the arm 243 (seen in Figs. 1 and 12) mounted upon the same shaft with the Geneva driving member 141 trips the microswitch 244 and the solenoid 310 (seen in Fig. 10) is actuated and the web severing knife 235 flips outwardly from the bed roll 28 and severs the web 15. The machine is so timed that the severing of the web occurs on the portion of the web between the guide roller 29 and the web winding station e. At the same time, the crescent-shaped locking member 149 on the Geneva drive wheel 141 has escaped from the member 139 mounted upon the Geneva driven member 134 and the Geneva driving roller 148 is entering one of the slots 140 on the Geneva driven member 134. The turret 44 begins to rotate and the wound roll of paper is moved from the web winding station e to the core stripping station f. In moving through this arcuate distance, the core shaft 43 frictionally engages the arcuate surface or edge 49 of the bracket member 50 and the core shaft continues to be rotated even though the pulley wheel 120 has moved from engagement with the double V belt 48. The rolls of paper formed on the core segments therefore continue to rotate and the tails or ends of the roll which are now free move over a brush 51 extending transversely of the machine and positioned between the web winding station e and the core stripping station f. As the tails of the rolled paper rub over the brush 51, an electrostatic charge is placed upon the tail of the roll. This charge is opposite in polarity to the normal charge existing in the remainder of the wound roll and the tail of the paper is attracted thereto and immediately clings to the roll. This eliminates the need of glue or moistening devices, etc., for causing the trailing end of the roll to cling or fasten itself to the roll.

Simultaneously with the moving of the mandrel and cores from the web winding station e to the stripping station f, the retractile arm 243 disengages from the free end of the core shaft and moves to the retracted position. When the core segments and shaft have reached the stripping station f, the retractile arm is completely withdrawn from the end of the core shaft and the rolls of paper may be stripped from the shaft.

At this time the arm 243 has rotated to a position in which it trips the limit-switch 236 and the stripping motor 102 is thereby actuated. The belt 101 forming a conveyor rotates and the lug 110 is moved into a position in which it engages the wound roll of paper adjacent the fixed end of the mandrel. As the lug 110 continues to move axially along the mandrel or core shaft, it pushes the rolls of paper from the shaft and onto the belt 101. The belt or conveyor 101 moves the completed rolls from the machine and onto another conveyor or into boxes, etc. The belt 101 carries the lug 110 to a position intermediate the ends of the machine and to a position in which the portion of the belt having the lug 110 secured thereto forms the lower or under surface of the continuous belt. In this position the lug triggers the microswitch 113 and the circuit for the motor 102 is broken and the stripper is

shut off. The Geneva driving assembly rotates the turret 44 to move the core shaft 43, which is now empty, from the core stripping station *f* to the station *a*. While in this position an operator may insert a new and unsegmented core length onto the core shaft. Subsequently the core shaft is again rotated through an arcuate distance, in the manner heretofore described, to the core cutting station *b*.

In moving from station *a* to station *b*, the core cutting knives mounted upon the rock shaft 54 have rocked or pivoted into a position in which the lower cutting disk assemblies 46 are clear of the arc through which the core shaft moves and the core shaft may freely enter between the upper and lower cutting disk assemblies. As the core shaft moves upwardly, the cutter control bearing 88 engages the lever 89 and the rock shaft 54 is pivoted to a position in which the upper and lower core cutting assemblies 46 are in the core cutting position. The knurled portion of the roller 86 which is continuously driven frictionally engages the core length 87 mounted upon the core shaft and causes it to rotate. The core length 87 is thereby cut into segments of desired length and the cut is accurately aligned and a complete peripheral cut is accomplished. It is to be noted that the cutting assemblies can be accurately adjusted by means of the adjusting screws 69 and 78 to insure a complete severing of the segments, while the cutting disks 58 need not be adjusted so that the knives exert a great pressure against the hardened surfaces of the core shafts 43. The cutting life of the disks is thereby substantially increased without loss of clean, complete severing. The springs 64 resiliently urge the cutting disks 58 into engagement with the cores 87.

When the Geneva drive again rotates the turret, the core shaft having the cut core length thereon moves upwardly through an arcuate distance and the bearing 88 forces the lever 89 upwardly and the rock shaft 54 pivots to a position in which the upper core cutting assemblies 46 move outwardly from the arc of travel of the core shaft. The core shaft then freely moves from the core cutting station *b* to the station *c*. When the bearing 88 moves free of the lever 89, the weight of the core cutting assemblies 46 rocks the shaft 54 to its most extreme position in the opposite direction and the lower core cutting assemblies 46 are in a position to receive the following core shaft and core. The stop 89a limits the downward movement of the lever 89. Thus, a complete cycle of operation has been completed.

It is to be understood that the turret assembly 44 is intermittently driven so that the core shafts move smoothly from one station to another and are then held or locked for a predetermined time in the various stations while the operations discussed are performed. Both the movement and locking of the turret, etc., is accomplished by the Geneva drive assembly. It is also to be understood that the operations performed at the various stations are carried on simultaneously and that while a core is being wound with a web at station *e*, the wound rolls are being simultaneously stripped from a core shaft at station *f*, and at the same time a core is being segmented at station *b*.

In order to facilitate and insure the adherence of the free or severed end of the web 15 to the core being moved into the web winding position, the mandrel and turret assembly as well as the driving assembly that rotates the turret intermittently are mounted upon hangers or brackets 45 that are mounted upon the ends of the top cross roller E adjacent to and outside of the end frames B and C. The hangers 45 are free to rock or pivot about the cross roller E. The hanger 45 adjacent the end frame B is equipped with a counterweight 152 that urges the hangers rearwardly. A rotatably-mounted roller 153 is positioned to engage the periphery of the Geneva driving member 141 as may be seen in Fig. 4. Since the roller 153 is secured to the end frame B through a suitable bracket member, and the Geneva driving member 141

is carried by the pivotal hanger 45, the engagement of the roller with the periphery of the Geneva driving member has the effect of holding the hanger at a predetermined position and in this position a core and mandrel in the web winding station *e* are spaced from the bed roll 28. However, the periphery of the Geneva driving member 141 is equipped with an indentation or cam 147 which is adapted to receive the roller 153. When the roller 153 is received within the cam 147, the resulting force created by the counterweight 152 pivots the hangers rearwardly to a position in which a core and mandrel moving into the web winding station *e* are urged into abutting relation with the bed roll 28. Since the free end of the web 15 lies on the periphery of the bed roll 28, it is picked up by the core, which has previously had glue applied thereto. The web is thus attached to the core and the hangers are pivoted outwardly by the engagement of the Geneva driving member 141 and the roller 153 to move the core and mandrel a spaced distance from the bed roll 28, so that the web may be wound thereon.

In the event a break in the web 15 occurs during the operation of the machine, the web is again threaded through the roller assemblies in the manner previously described and the hand wheel 196 is withdrawn outwardly from the end frame B to remove the timing gear 194 from the gear train. The hand wheel 196 may be rotated to move another core and mandrel into the web winding position, and the machine is again ready for operation upon moving the hand wheel inwardly to engage the timing gear 194. The machine is automatically timed, because the arm 243 that actuates both the core stripping mechanism J and the web severing knife 235 is carried by the stub shaft 143 upon which the Geneva driving member 141 is mounted. Therefore, rotation of the hand wheel 196 to move a new core into the web winding station is accomplished by the rotation of the Geneva driving member 141 and this automatically insures rotation of the arm 243. The arm, then, is always properly positioned with respect to the switch 244 which actuates the web severing knife and the switch 236 which actuates the core stripping assembly J.

The web winding machine may be adapted to wind rolls of paper, etc., having a greater or less quantity of webbing wound thereon by simply changing the timing gear 194. To do this, the nut 226 and washer 225 are removed and the hand wheel 196 and timing gear 194 withdrawn from the axle 195. The bolt 224 is removed to free the timing gear 194, and a gear having a larger or smaller diameter, as desired, is secured to the hand wheel. The nut 232 is then loosened to permit adjustment of the idler gear 193 and the hand wheel and timing gear are replaced on the axle 195. The idler gear 193 is positioned in the slot 229 to obtain the desired meshing of the timing gear 194 and the idler gear 193, and the nut 232 is then tightened to lock the idler gear 193 in position.

Changing the size of the timing gear 194 will change the rotational velocity of the axle 195 and consequently the gear 197 which is mounted thereon. Since the gear 197 drives the Geneva driving member 141 through the gears 198 and 199, the Geneva driving member 141 will therefore rotate at a different speed and the turret 44 and mandrels fixed therein will rotate at a speed corresponding to the new speed of the Geneva driving member, and thus more or less webbing will be wound upon each core, depending upon the size of the timing gear 194. It is to be understood, of course, that the bed roll 28 and the other rollers constituting the web feeding and conditioning assembly will continue to rotate at the same speeds, unaffected by the change in the timing gear 194.

The web winding machine of our invention winds a tight and solid roll of webbing upon the cores, and a neat and attractive roll of paper, etc., is thereby produced. A roll of this nature results, to a great extent, from the adjusting means incorporated to permit accurate web ten-

sioning, while accomplishing this without increasing the possibilities of web breakage. At the same time, the web slitting knives releasably engage the web slitting roll so that the web may be easily and rapidly threaded through the machine. In addition, the driving assembly, which itself is continuously driven, rotates the turret and mandrels intermittently, and between movements the driver locks the turret, with the result that the mandrels or core shafts are locked in their stations while the various operations are being performed. The core cutting knives are adjustable so that a complete severing of the cores may be obtained while excessive pressure between the cutting knives and core shafts is eliminated. The core cutting knife assemblies are axially adjustable upon their mountings so that the length of the core segments will exactly correspond with the width of the slit web strips. Yet, this is accomplished without increase in the care with which the core lengths must be placed upon the core shafts. When the core shafts are in station *a* the operator simply inserts a tubular core and seats it firmly against the stop rings with which the core shafts are equipped. This is a simple operation, since the stops limit the axial insertion of the cores onto the shafts at the proper point.

A minimum of adhesive or glue is used, since the glue applicator wheels 47 are knurled and are rotatably driven while the cores are moved over the peripheries of these wheels. The wheels are also spaced apart and narrow rings of glue are applied to the cores, and the knurled periphery of the wheels permits a thin layer of glue to be applied. Any excess glue on the applicator wheels is returned to the glue pot where it may again be used. Also, the structure placing an electrostatic charge on the tail of the wound rolls so that the tail will cling to the roll eliminates the necessity of using glue for this operation. In addition, since no glue is used for this purpose, every sheet of webbing on the roll may be used by the consumer and the wastage that normally accompanies the gluing of the tails is no longer encountered.

The stripper assembly automatically strips the full cores from the machine when the full or completed cores are rotated into the core stripping station *f*. The stripping operation is accomplished rapidly, without damage to the full rolls. The continuous belt supports the full cores, while the laterally-extending lug carried by the belt gently engages the end of the roll adjacent the turret and pushes the full cores from the core shaft and onto the continuous belt. No damage to the rolls occurs as the completed rolls are moved into the stripping position, because at this time the cores are free to rotate on the mandrels and the mandrels themselves are free to rotate. In the event, then, that the rolls should abut the edge of the belt, they simply rotate as the mandrel is moved completely into the core stripping station and no damage to the rolls will result.

No longer is it necessary for an operator to thread core segments onto the mandrels, nor is it necessary for the operator to manually remove the full cores from the machine. Heretofore, for the sake of rapid operation the operator has had to remove the core shaft carrying full cores from the machine and to replace the removed core shaft with another upon which cores have been received. The removal of the full cores from the core shaft was then accomplished outside of the machine. Now, the stripping or removing of the full cores from the machine is accomplished automatically and the operator has now only to place core lengths that have not been segmented onto the mandrels. Our web winding machine does the rest. The saving in labor is substantial and the cost of producing rolls of paper, etc., is therefore greatly decreased. Further savings result from the rapidity with which full cores are turned out by our machine. The machine is rugged and sturdy, and maintenance requirements are at a minimum.

With a conventional web rewinding machine, the operator removes the mandrel with the finished wound stock,

strips off the wound material from the mandrel, threads on new cores, and places the core-clad mandrel back into the machine. As the mandrel itself normally weighs 12 to 15 pounds, it can readily be seen that this is a fatiguing task. It also limits the speed of the machine to the number of mandrels per minute that the operator is able to handle throughout the day. In our web rewinding machine, however, with mandrels fixed in the machine, the operator only has to thread on a long core weighing a few ounces; or, if so desired, a hopper may be provided from which the cores can be threaded automatically onto the mandrels, thus making the machine fully automatic.

While in the foregoing specification we have described a specific embodiment of our invention in considerable detail for purposes of clear illustration, it is understood that the details may be varied widely by those skilled in the art without departing from the spirit and scope of our invention.

We claim:

1. In a web winding machine, a frame, a turret rotatably mounted within said frame adjacent one end thereof, driving means continuously driven and adapted to rotate said turret intermittently, a plurality of elongated core shafts fixed at one end to said turret at points equally spaced about an arc having its center on the rotational axis of said turret and having free ends projecting inwardly from said turret in substantially parallel relation, each of said core shafts being adapted to receive at one position of the turret an elongated tubular core, support means carried by said frame and movable into engagement with the free end of a core shaft at selected positions thereof to support the same, locking fingers carried by each core shaft for gripping a core positioned thereon to prevent rotational movement thereof relative thereto and being actuated by said last-mentioned means, means for winding a web upon the core of a core shaft while the free end thereof is supported, means for withdrawing said support member from the free end of the core shaft, and automatic means for removing the wound core from the core shaft including a continuous conveyor and a laterally-extending lug carried thereby, said lug being movable into engagement with a full core by the movement of said conveyor to move a full core from the core shaft while the core shaft remains fixed to said turret.
2. The structure of claim 1 in which the core shafts have pointed free ends and the support means therefor is provided with a recess for receiving said pointed ends.
3. The structure of claim 2 in which said automatic means includes a continuous belt and a laterally-extending lug mounted thereon, said lug being carried by said belt into engagement with the end of a full core adjacent the fixed end of said mandrel to push the full core from the mandrel.
4. In a web rewinding machine, a frame, a turret rotatably mounted in said frame adjacent one end thereof, a plurality of core shafts fixed at one end to said turret and projecting inwardly therefrom in substantially parallel alignment, means for rotating said turret intermittently to move said core shafts through spaced arcuate distances defining operating stations, each of said core shafts being adapted to receive a core thereon at one station of the turret, and means for simultaneously cutting a core into segments at one station of said turret, for winding a web upon said cores at another station of said turret, and for stripping filled cores from the core shafts at still another station of said turret, all of the operations being carried on while said turret is stationary, each of said core shafts being equipped with a bore extending axially therethrough and having a plurality of axially spaced peripheral slots communicating with the bore, a rod slidably mounted in said bore, a plurality of fingers pivotally mounted upon said rod and being adapted to project through said slots at one position of said slideable rod and to be drawn into said slots at another position of said rod, means carried by said frame

and being movable into engagement with said rod to project said fingers through said slots when said core shaft is in the web winding station, and means for withdrawing said last mentioned means from the end of said rod to release said fingers when said core shaft is in the core stripping station.

5. In a web rewinding machine having a frame and a turret rotatably mounted therein for moving core shafts into web winding and core stripping stations, at least one core shaft mounted on said turret, said core shaft being equipped with a bore extending axially therethrough and having a plurality of axially spaced peripheral slots communicating with the bore, a rod slidably mounted in said bore, a plurality of fingers pivotally mounted upon said rod and being adapted to project through said slots at one position of said slidable rod and to be drawn into said slots at another position of said rod, means carried by said frame and being movable into engagement with said rod to project said fingers through said slots when said core shaft is in the web winding station, and means for withdrawing said last mentioned means from the end of said rod to release said fingers when said core shaft is in the core stripping station.

6. In apparatus of the character described, a core shaft adapted to be moved through a plurality of operating stations and being adapted to receive and support a core thereon, said core shaft being provided with a bore extending axially therein and having a plurality of axially spaced peripheral slots communicating with said bore, a rod mounted within said bore for axial movement relative thereto, a plurality of fingers pivotally carried by said rod and being adapted to project through said slots when said rod is in one axial position within said bore and to be drawn into said slots when said rod is in another position within said bore, means provided by said apparatus for engagement with said rod to project said fingers through said slots when said core shaft is in one operating station, and means for withdrawing said last mentioned means from the rod to release said fingers when said core shaft is in another operating station.

7. In a web rewinding machine, a frame, a hanger pivotally supported on said frame, a turret rotatably

mounted on said hanger and equipped with a plurality of mandrels extending freely outwardly therefrom at spaced-apart arcuate distances, drive means for rotating said turret to move said mandrels progressively through a plurality of operating stations, one being a web rewinding station, a bed roll adjacent said web rewinding station and being adapted to have a web drawn thereover, said hanger being balanced so as to bias said mandrels when in said web rewinding station toward engagement with said bed roll, and counter-acting means operatively arranged with said frame and drive means for overcoming the bias of said hanger to space mandrels when in said web rewinding station from said bed roll except just prior to the movement of each mandrel into the web rewinding station whereby a web at the surface of said bed roll is engaged and picked up by cores supported on the mandrels.

8. The web rewinding machine of claim 7 in which said hanger is equipped with a counter-weight, said counter-weight being effective to bias said hanger.

9. The structure of claim 7 in which said counter-acting means comprises a roller carried by said frame and a cam provided by said drive means and having a cam surface engaged by said roller.

25 10. The structure of claim 9 in which said drive means comprises a Geneva drive and in which said cam is provided by the Geneva drive wheel.
